Charles H. Keane,

INVENTOR:

Henry C. Thomson

UNITED STATES PATENT OFFICE.

HENRY C. THOMSON, OF BOSTON, MASSACHUSETTS.

EYEGLASSES.

SPECIFICATION forming part of Letters Patent No. 698,078, dated April 22, 1902.

Application filed March 28, 1901. Serial No. 53,310. (No model.)

To all whom it may concern:

Be it known that I, HENRY C. THOMSON, a citizen of the United States, residing at Boston, Suffolk county, State of Massachusetts, 5 have invented a new and useful Improvement in Eyeglasses, of which the following is a description.

My invention relates to the means of holding the lenses of eyeglasses in such position 10 and with such fixity that oscillation, looseness of setting, and the coming out of any of the screws will be avoided.

My invention as an entirety consists in a spring-piece of resilient metal having a base 15 properly perforated and projecting ends thereof curved like the lenses and spring clamping-arms, and this entirety is made up of parts which may be separately used.

My invention will be easily understood by 20 reference to the accompanying drawings, in which—

Figure 1 is a plan of a pair of rimless eyeglasses including my invention in its entirety. Fig. 2 is a horizontal sectional view 25 of part of Fig. 1. Fig. 3 is a view in perspective of my entire invention, excepting one screw. Fig. 4 is a plan of a lens and its metallic supporting parts as ordinarily made. Fig. 5 is a view in perspective of a part of 30 my entire device as shown in Fig. 3; and Fig. 6 is a plan of a part of that part of my invention shown in Fig. 5 placed in the ordinary holding device.

Similar letters refer to similar parts in the 35 figures.

A is a rimless lens.

B is the ordinary holding spring or piece, of 40 any desired construction, either integral or composed of two pieces passing each other and held by the screw G.

C C are the ordinary nose-guards.

D is the ordinary metal clamp by which, as illustrated in Fig. 4, the lens A is usually sustained.

45 D' is the shank.

E being my entire device, as shown in Fig. 3, is made up of the washer part F, so perforated at f' as to enable it to lock the termination g of the screw G, the vertical curved

50 extensions f f, and the lateral spring-clamps e e, perforated (or slotted, if preferred) at d'.

The function of this spring-clamp e e is to hold the screw d from turning.

G is a holding-screw and has a square or other irregular projecting part g, adapted to 55 fit into the perforation or slot f', whereby the screw G will be prevented from turning.

It will be seen that in Fig. 5 the metal holding-piece has only the washer part F perforated at f' and the spring-arms e e perforated 60 at d' d', but does not have the projecting arms f f.

In Fig. 6 it will be seen that the metal holding-device D, having the shank D' and the two arms D, is the ordinary form for holding 65 the glasses, as shown in Fig. 4, but that there is also shown in Fig. 6 the washer part F, perforated at f', omitting the spring-arms e e and the extension-arms f f.

If the entire device shown in Fig. 3 be used, 70 it is evident that the screw G is permanently held from turning by the locking between g and f', and the screw d is held from turning by the spring-clamp e e, and the same is true if only the parts shown in Fig. 5 be used. If 75 only the washer part F, perforated at f', of Fig. 6 be used, that washer will prevent the screw G from turning, because itself held from turning by being placed between the arms D D of the ordinary holding device. It 80 will also be seen that as shown in Fig. 1 my entire device as shown in Fig. 3 is placed within the ordinary jaws or holding-pieces D, omitting the ordinary extensions f' shown in Fig. 4, for which the extensions f f are used. 85 It will also be observed that by my construction it is not necessary to groove the edge of the lens.

Having described my invention, what I 90 claim is—

1. In an eyeglass, in combination with the usual nose-guard, bow, lens, and holding-clamp, a washer F, having the angular perforation f' placed vertically between and held rigidly by the projecting arms of the holding-clamp against the edge of the lens, and a holding-screw G having its termination g, adapted to fit said perforation f' to prevent said holding-screw G from turning; substantially 95 as described.

2. In an eyeglass, in combination with the nose-guard, bow, lens, and usual holding-

clamp, a spring-clamp having the part F angularly perforated at f' , and having also the spring-arms e e perforated at d' d' , and a holding-screw G having its termination g adapted to fit the perforation f' to prevent said holding-screw G from turning; substantially as described.

3. In an eyeglass, in combination with the usual nose-guard, bow, lens, and holding-
5 clamp, a spring-clamp E, composed of the part F angularly perforated at f' , and having also

the extensions f f and the spring-arms e e perforated at d' d' , and the screw G having its termination g adapted to fit the perforation f' to prevent said holding-screw G from turning; substantially as described. 15

In witness whereof I hereunto set my hand this 25th day of March, 1901.

HENRY C. THOMSON.

In presence of—

CHARLES H. HANSON,

FRED C. CHAMBERLIN.
